CLAIM

I claim the ornamental design for a pill box, as shown and described.

DESCRIPTION

FIG. 1 is a perspective view of a pill box showing my new design;

FIG. 2 is a top view thereof;

FIG. 3 is a bottom view thereof;

FIG. 4 is a side view thereof, the opposite side being a mirror image;

FIG. 5 is an end view thereof, the opposite end being a mirror image; and,

FIG. 6 is a perspective view thereof with some covers in open position.
